UNITED STATES PATENT OFFICE.

EDITH LANOUETTE, OF BOSTON, MASSACHUSETTS.

DRAWERS.

No. 856,268.

Specification of Letters Patent.

Patented June 11, 1907.

Application filed September 24, 1904. Serial No. 228,731.

To all whom it may concern:

Be it known that I, EDITH LANOUETTE, a citizen of the United States, residing at Boston, county of Suffolk, State of Massachusetts, have invented an Improvement in Drawers, of which the following description, in connection with the accompanying drawing, is a specification, like letters on the drawings representing like parts.

10 This invention relates to drawers for women and children, and especially to the class of drawers known as "closed drawers," and it has for its object to provide a garment of this class which is more comfortable than closed drawers as ordinarily made.

15 My improved drawers are made with a yoke portion which extends entirely around the waist thereof, and which is shaped to fit the waist and hips of the wearer, said yoke 20 portion being divided vertically at either the front or rear, but preferably at the rear.

25 The necessary opening in the drawers is provided for by making them with a flap, the upper edge of which is detachably secured to the lower edge of the yoke portion. By 30 making the drawers with the yoke portion which snugly fits the hips the garment can be worn underneath a corset, waist, or other upper garment without any such wrinkling, 35 puckering, or gathering of the portion of the drawers underlying the corset as to be uncomfortable, and the necessity of a waist-band at the upper end of the drawers is obviated. The yoke portion is of such a depth 40 that the upper edge of the flap comes below the overlying corset, waist, or other upper garment, so that said flap may be conveniently opened.

45 In the drawings, Figure 1 is a front view of 40 a pair of drawers embodying my improvements, and Fig. 2 is a rear view thereof.

50 The top of the drawers is made with a yoke 3, which extends completely around the garment, said yoke portion being shaped to 55 fit over the hips of the wearer, so that when the drawers are on said yoke portion is smooth and without wrinkles. The yoke is divided, either at the front or rear, but preferably at the rear, as shown at 4, and the 60 two meeting ends of the yoke may be detachably secured together in any suitable way, as by means of hooks or buttons, buttons 5 being shown in this embodiment of my invention. The leg portions 7 of the drawers are 65 secured to the lower edge of the yoke, and as said leg portions are fuller than the yoke I

propose to gather them thereto. Either the front or the rear of the drawers, but preferably the rear, is provided with a flap 6, the upper edge of which when it is closed being 60 adapted to meet and be detachably secured to the lower edge of the rear portion of the yoke. In this form of my invention the flap has the yoke 8 at its upper edge, to which the body of the flap is secured, and as the yoke 8 65 is made to fit the bottom of the hip yoke 3 the material of the flap which is considerably fuller than the yoke 8 will be gathered to said yoke as shown. The flap may be secured to the yoke 3 in any suitable way, as 70 by hooks or buttons 9.

Extending around the bottom of the hip yoke 3 is a gathering string 10, which extends from one side of the flap around the front of the yoke 3 to the other side of the flap, and 75 extending across the body of the flap is another gathering string 11. By tying together the ends of the gathering strings 10 and 11 at each edge of the flap, the size of the yoke 3 may be adjusted to snugly fit the 80 wearer. These gathering strings 10 and 11, however, are not essential to my invention. Because the yoke portion 3 fits snugly around the hips it is possible to wear my improved drawers beneath the corset, waist, or 85 other similar garment without any of the objectionable wrinkling or puckering in the drawers which inevitably results where the full body of the drawers is gathered to a waist-band. 90

I propose to make the yoke 3, especially that portion thereof to which the flap 6 is secured, of sufficient depth so that its lower edge and consequently the upper edge of the flap 6 comes below the corset or other waist, 95 so that said flap may be conveniently opened or closed without unbuttoning or disturbing the corset or waist. By making the garment with the yoke 3, and also making the flap 6 with the yoke 8, a perfect fit can be 100 secured, thus making the garment an extremely comfortable one to wear. Moreover, the presence of the yoke 3 permits of the application thereto of ruffles or other padding for the hips, if desired. 105

My invention is equally applicable to drawers or underdrawers, and has many advantages when embodied in children's drawers, or underdrawers.

My invention may be embodied in a garment made of any of the usual materials used in making garments of this class, such

as linen, cotton, silk, stockinet, jersey, woolen goods, etc.

Having described my invention, what I claim as new and desire to secure by Letters

5 Patent, is:—

1. In a garment of the class described, a yoke extending completely around the waist and divided at the back, means to detachably secure together the meeting edges of the 10 yoke, and leg portions secured to the bottom edge of the yoke, said garment having a flap at its rear provided with a yoke at its upper edge to which the upper edge of the material of the flap is gathered, the flap being 15 fuller than the yoke, means to detachably secure said latter yoke to the lower edge of the rear of the first-named yoke, a drawing string extending around the lower edge of the yoke from one edge of the flap to the 20 other, and another drawing string extending across the flap, whereby by tying the

ends of the drawing strings the yoke may be adjusted to snugly fit the wearer.

2. In a nether garment, the combination with a yoke adapted to extend completely 25 around the waist, with leg portions secured to the bottom of the yoke and provided with a rear flap, means to detachably secure the upper edge of the flap to the lower edge of the yoke, a drawing string extending around the lower edge of the yoke, and another drawing string extending across the flap, whereby by tying together the ends of the drawing strings the yoke may be adjusted in size to snugly fit the hips of the wearer. 30

In testimony whereof, I have signed my name to this specification, in the presence of two subscribing witnesses.

EDITH LANOUETTE.
